UNITED STATES PATENT OFFICE.

JOHN H. HANLON, OF SOMERVILLE, MASSACHUSETTS.

TRACK-SANDING DEVICE.

No. 841,144.

Specification of Letters Patent.

Patented Jan. 15, 1907.

Application filed May 16, 1906. Serial No. 317,088.

To all whom it may concern:

Be it known that I, JOHN H. HANLON, a citizen of the United States, residing at Somerville, county of Middlesex, State of Massachusetts, have invented a certain new and useful Improvement in Track-Sanding Devices, of which the following is a specification, reference being had therein to the accompanying drawings.

10 My invention has for its object to produce certain improvements in pneumatic track-sanders for locomotives, and relates particularly to the nozzle which is employed within the sander to emit the air under pressure and 15 to the means for cleaning the nozzle if it becomes clogged.

It also has to do with means for preventing the excessive wear on the structure caused by the projection of sand against the 20 metallic walls of the pipes.

It has been found in connection with the use of these sanders, especially on new locomotives, that pieces of scale which jar loose from the pipes find their way into the air-nozzle and clog the air-discharge aperture, so that the sander becomes ineffective when 25 this occurs. A great variety of other foreign substances find their way to the nozzle of the sander, particularly from the air-pump—such as grease and gum, bits of waste or packing, and even slivers of metal—in addition to the scale from the pipes. It is desirable that the nozzle be constructed so that it will be unlikely to become clogged 30 when in use and so arranged that if it does become clogged it can be easily and quickly cleaned.

My present invention provides a new and improved air-nozzle which does not readily 40 clog and also a convenient means for removing the air-nozzle if for any reason it does become clogged.

Great difficulty has also heretofore been found in track-sanders because the sand which is projected by the blast of compressed air from the nozzle tends to cut out very rapidly any metallic wall which the sand strikes against. Attempts have heretofore been made to minimize this effect by employing hardened steel at the points where 45 this occurs. I find, however, that the difficulty may be effectively overcome by constructing a pocket opposite the sand-blast. This pocket rapidly fills with sand, which 50 forms a cushion or buffer which protects the

walls of the pocket from the sand from the blast. By arranging this pocket at the proper angle with the line of motion of the particles of sand it is found that there is but slight loss of velocity by the sand. 60

For convenience of illustration I have shown in the accompanying drawings my improved nozzle and clean-out device as applied to a track-sander of the kind illustrated in United States Letters Patent No. 737,228, 65 granted to me August 25, 1903, and No. 797,890, dated August 22, 1905.

The invention will be fully understood from the following specification, taken in connection with the accompanying drawings, and the novel features thereof are pointed out and clearly defined in the claims at the close of the specification. 70

In the drawings, Figure 1 is a view, partly in section, of a portion of a sand-dome, a 75 sander attached thereto provided with my improved nozzle, and the clean-out device in place ready to remove the nozzle. Fig. 2 is a view, partly in section, of the nozzle itself removed from the sander. Fig. 3 is a view of 80 the scale-stopping device. Fig. 4 is an end view of my improved nozzle looking from the left as seen in Fig. 2. Fig. 5 is a view in section, showing the pocket opposite the air-nozzle and the cushion or buffer in the said 85 pocket.

Referring to the drawings, 11 is a portion of the side wall of the sand-dome, to which is attached the sand-collector 12 on the inside of the sander. The sand-discharge pipe 13 90 is provided with a clean-out opening 14, by means of which the interior of the sander may be reached. At 15 is shown the hood, and at 16 the clean-out opening by means of which the sand-inlet holes 17 are reached to 95 remove pebbles and other foreign substances which may clog these holes. These parts are substantially as shown in my Letters Patent heretofore referred to. Within the sander or sand-collector 12 is located the air-discharge nozzle through which the compressed air which operates the sander is admitted to the interior of the track-sander. The expansion of the air at the point of the nozzle draws the sand in from the sand-dome 100 through the sand-holes 17.

The construction of the air-discharge nozzle will be plainly seen by reference to Fig. 2 of the drawings. It consists in a nozzle 18, which is screw-threaded at one end, as 110

shown at 19, for engagement with the corresponding tapped hole in the sand-collector 12. The other end of the sand-nozzle 18 is constructed in the form of a frustum of a 5 square pyramid, as shown at 20, so that it may be readily engaged by a socket-wrench 21, (see Fig. 1,) by means of which the said nozzle 18 may be unscrewed from the sander 12 and withdrawn when it is desired to clean 10 the said nozzle 18. The nozzle 18 is provided with an air-aperture 22, which is expanded at the point, as seen at 23, by counter-boring, so that a circular shoulder 24 is formed, which assists in preventing the sand 15 which may lie in front of the nozzle within the cavity of the body 12 of the sander from jarring or otherwise working back into the air-emission aperture of the air-nozzle when the locomotive is in motion and the sander is 20 not in operation.

At the other end of the air-discharge nozzle there is located an interior scale-collector 25, which is shown in detail in Figs. 2 and 3. This scale-collector is screw-threaded at its 25 left-hand end, as shown at 26, and engages corresponding screw-threads cut on the interior of the bore of the air-nozzle. The exterior diameter of the scale-collector 25 is considerably less than the interior diameter of 30 the air-nozzle 18, so that a space 28 is left around the scale-collector 25 and between it and the air-nozzle 18. The scale-collector 25 is hollow and is provided with a variety of air-inlets. One of them, 29, is a continuation 35 of the interior bore. The end of the scale-collector 25 is as nearly pointed as it can be, so that bits of any foreign substance are less likely to lodge in the hole at the end of the said scale-collector. Two other circular 40 apertures 30 and 31 are opposite each other near the screw-threaded end 26. Four slits 32, two of which are shown in Fig. 3, are also sawed or otherwise formed lengthwise of the scale-collector.

45 It will be seen that the arrangement of the air-apertures is such that if one or two of them become clogged the others will operate, and thus the scale is not likely to prevent the working of the sander. Furthermore, the 50 arrangement of the air-apertures is such that the action of the air tends to clear the holes if any of them become clogged. For instance, if the hole 29 becomes clogged there is formed a back pressure of the compressed 55 air within the scale-collector which tends to remove the foreign substance from the hole 29; but whether the foreign substance is removed by the air or not air will continue to be admitted to the air-nozzle through the 60 slits 32 and the holes 30 and 31. If one of the slits should become clogged, which is very unlikely, because, as is well known, a slit is much more difficult to clog than a circular hole, the air which is entering to the 65 interior of the scale-collector will tend to

force the obstruction out of the clogged slit. Furthermore, the action of the compressed air upon any scale which may collect in the space between the scale-collector and the inside wall of the air-discharge nozzle tends to cause the scale to be violently agitated in this space and to break up and wear away the said particles of scale, so that eventually they become small enough to pass through the air-apertures 30 and 31. It is found in 70 actual operation that this arrangement of parts permits the sander to be used very successfully, even upon new locomotives from whose pipes considerable amounts of scale are likely to jar loose. 80

When it is desired to remove the nozzle for any reason—as, for instance, if the nozzle should become wholly or partly clogged—it may be done in the following manner without removing the sand from the sand-dome: 85 The plug 301, which ordinarily closes the clean-out 14, is removed and a tube 33, of some suitable thin material—as, for instance, tin—is inserted. This tube cuts through the sand and is of a length sufficient to reach 90 into the interior of the body of the sander 12 and inclose the nozzle 18, thus preventing sand from the sand-dome falling through the sand-inlet holes 17. The compressed air is then turned on for an instant. Even if the 95 air-discharge nozzle is badly clogged sufficient air will find its way through, so that the sand in the tube 33 will be blown out. This is frequently not necessary, as only a small amount of sand will find its way into the 100 tube 33, and the amount is not sufficient to interfere with the operation of a wrench, by means of which the air-discharge nozzle is removed. A socket-wrench 21 is then inserted and brought into engagement with the 105 end of the air-nozzle 18 and the air-nozzle unscrewed. By forcing the socket-wrench firmly onto the tapering end of the air-nozzle it will be found that when unscrewed the air-nozzle will come away with the socket-wrench, so that it may be withdrawn from the tube. It is then cleaned by the removal 110 of the scale-collector 25 and may be reinserted in the same manner. The air is also turned on again for an instant after the nozzle is removed, so that the pipe itself is blown 115 clear. The parts may then be replaced.

In Fig. 5 there is shown the pocket in which is formed the sand cushion or buffer which prevents the sand cutting out the pipe 120 at the point opposite the air-nozzle 18. In the drawings I have shown this pocket as formed in one-half of a V connection 40, the other branch of which is connected to the sand-delivery pipe 42. The sand which is 125 set in motion by the air collects in the branch 14 until it is filled, as shown at 43, so that the plug 301 is completely protected from the flying sand by the sand which piles up in front of it. This cushion of sand effectively 130

prevents injury to the parts, but may be easily removed when it is desired to get at the air-nozzle to clean it. By making the pocket in a **V** connection the other branch of which diverges at a small angle from the line of motion of the sand I find that the loss of velocity by the sand is very slight.

5 Pockets or sand-cushions such as I have described may be located opposite any sudden change of direction in the sand-discharge pipes of a pneumatic track-sanding system.

10 What I claim is—

15 1. The improved air-nozzle for track-sanders, having a tapering end for engagement with a socket-wrench.

20 2. The improved air-nozzle for track-sanders, having one end tapering for engagement with the socket-wrench and the other end screw-threaded for engagement with the body of the sander.

25 3. In a track-sander, the combination of sand-collector, an air-discharge nozzle and a scale-collector within the said air-discharge nozzle.

40 4. In a track-sander, the combination of a sand-collector, an air-nozzle screwed into the interior of the said sand-collector, and a scale-collector within the said air-nozzle screwed to the interior thereof.

35 5. The improved air-nozzle for sand-collectors, comprising a nozzle-body, having an air-aperture and an enlarged bore, and a scale-collector within the said enlarged bore having an exterior diameter less than the interior diameter of the said enlarged bore.

40 6. The improved air-nozzle for sand-collectors, comprising a nozzle-body having an air-aperture, an enlarged bore and a scale-collector within the said enlarged bore, provided with air-apertures in the form of slits.

45 7. The improved air-nozzle for sand-collectors comprising a nozzle-body having an air-aperture, an enlarged bore and a scale-collector within the said enlarged bore pro-

vided with air-apertures in the form of slits 45 and circular holes.

8. The improved clean-out device for track-sanders, which comprises a tube enclosing the air-nozzle and reaching from the exterior of the clean-out to a point back of 50 the air-inlet holes.

9. The improved air-discharge nozzle for track-sanders having its air-discharge aperture counterbored to prevent the admission of sand to the interior of the air-discharge 55 nozzle.

10. The improved means for preventing the wear of sand-discharge pipes comprising a cushion or buffer of sand collected in a suitable pocket.

11. The improved means for preventing the wear of sand-discharge pipes which consists in a pocket opposite the point of discharge in which sand may collect and form a cushion or buffer.

12. The improved means for preventing the wear of sand-discharge pipes which consists of a **V** connection, one branch of which serves as a pocket opposite the point of discharge in which the sand collects to form a 70 cushion or buffer, and the other branch of which is connected to the sand-discharge pipe.

13. The improved means for preventing the wear of sand-discharge pipes which consists of a **V** connection, one branch of which serves as a pocket opposite the point of discharge in which the sand collects to form a cushion or buffer, and the other branch of which is connected to the sand-discharge 75 pipe, the angle between the said branches of the **V** connection being relatively small.

In testimony whereof I affix my signature in presence of two witnesses.

JOHN H. HANLON.
